Attorney

UNITED STATES PATENT OFFICE

JOHN GOGOL, OF NORTHAMPTON, MASSACHUSETTS

BRIDGE AND BREAKER

Application filed August 15, 1930. Serial No. 475,553.

This invention relates to certain new and useful improvements in a bridge and breaker.

The primary object of the invention is to provide a bridge and breaker construction wherein the piers of the bridge are set into the river bed with the piers arranged in groups of aligned series combined with a novel form of breaker spaced from and in line with each series of piers for breaking 10 the waves directed toward the piers to reduce wear thereon.

A further object of the invention is to provide a novel form of breaker embodying a wooden frame structure capped with a 15 metal plate secured to the frame structure by strap irons.

With the above and other objects in view that will become apparent as the nature of the invention is better understood, the same 20 consists in the novel form, combination and arrangement of parts hereinafter more fully described, shown in the accompanying drawings and claimed.

In the drawings:

25 Figure 1 is a fragmentary top plan view of a bridge and breaker constructed in accordance with the present invention, showing the plurality of series of aligned piers of the bridge structure with a breaker aligned with each series of piers;

Figure 2 is a fragmentary side elevational view showing the upwardly inclined breakers aligned with the piers;

Figure 3 is an end elevational view;

25 Figure 4 is a cross-sectional view taken on line 4—4 of Figure 3, showing the wooden frame structure of the breaker and the metal cap plate therefor; and

Figure 5 is a cross-sectional view taken on 40 line 5—5 of Figure 3, showing the strap iron for attaching the metal cap plate to the wooden frame structure of the breaker.

Referring more in detail to the accompanying drawings, the combined bridge and breaker includes a bridge structure having a flooring 10 laid upon a sub-structure 11 carried by a series of aligned piers 12 set into the river bed 13 as shown in Figure 3. The bridge further includes side posts 14 having 50 angle brace bars 15 and upper hand rails 16.

The series of piers 12 are arranged in spaced relation as shown in Figures 1 and 2 and a breaker is spaced from and aligned with each series of piers. Each breaker comprises vertical center piers 17 and inclined side piers 18 set into the river bed 13 as illustrated with the upper ends of the side inclined piers 18 at each end of the breaker connected by longitudinally extending boards 19 and an upper rail 20. The frame structure is upwardly inclined toward the series of piers 12 of the bridge as shown in Figs. 2 and 3 for breaking the water and waves when moving toward the piers.

An inverted V-shaped metallic cap plate 21 is mounted upon the upper side of the breaker to reduce wear on the wooden frame structure thereof, the cap plate 21 extending the full length of the breaker and being anchored in position by the strap irons 22. The 65 strap iron 22 is welded or otherwise secured as at 23 to opposite sides of the inner face of the cap plate 21, the intermediate portion 70 of the strap iron being engaged with the head rail 20 while the extended ends thereof 75 overlie the boards 19 with the terminal ends angularly bent as at 25 into engagement with the lower side edges of the lower boards 19 for anchorage to the inclined piers 18 as at 26.

From the above detailed description of the 80 invention, it is believed that the construction thereof will at once be apparent, it being observed that a breaker is aligned with each series of bridge piers 12 and that each breaker being of wooden construction is capped by a 85 metal plate to reduce wear thereon.

While there is herein shown and described the preferred embodiment of the invention, it is nevertheless to be understood that minor changes may be made therein without departing from the spirit and scope of the invention 90 as claimed.

I claim:

In a combined bridge and breaker, a bridge 95 having a series of aligned piers and an upwardly inclined breaker aligned with each series of piers, including a wooden frame structure and a metal cap plate therefor, and strap irons disposed beneath the cap plate for anchoring the cap plate to the breaker frame, 100

said cap plate being of V-formation extending down each side of the breaker frame and boards on the breaker frame over which the strap irons extend and retained in position by said strap irons.

5 In testimony whereof I affix my signature.

JOHN GOGOL.
